SPARK-PLUG.

1,259,267.

Specification of Letters Patent. Patented Mar. 12, 1918.

Application filed August 20, 1914, Serial No. 357,697. Renewed January 18, 1918. Serial No. 212,534.

To all whom it may concern:

Be it known that I, HENRY H. MORETON, a citizen of the United States, residing at Stony Point, in the county of Rockland and State of New York, have invented new and useful Improvements in Spark-Plugs, of which the following is a specification.

This invention relates to a sparking device capable of use for ignition purposes, or 10 in connection with any form of apparatus which, in operation, requires the passing of an electric spark between separated terminals.

One of the objects of the invention is to 15 provide a device of the character mentioned which will be simple in construction and efficient in operation as an ignition device for explosive engines, and the like. A further object is to provide means for increasing 20 the number of sparking points without decreasing the intensity of the current at any of the sparking terminals, and without necessitating an increase in current to maintain the same. A further object is to provide 25 a sparking device in which one of the sparking terminals is provided with means having a more or less condenser-like action, whereby an intense spark is obtained.

The invention will be hereinafter fully 30 set forth and particularly pointed out in the claims.

In the accompanying drawing:—

Figure 1 is a side elevation of a simple 35 form of spark plug embodying my invention. Fig. 2 is a side elevation of the modified form. Fig. 3 is a longitudinal sectional view of a second modification.

Referring to the drawing, 10 designates an insulating block of any suitable material, 40 such as mica, porcelain, or the like, and passing through said insulating block is an electric conductor 11, one end of which projects beyond the inner end of the insulating member to form a sparking terminal, as indicated at 12. If desired, the outer end of the conductor may be threaded to form a binding post as indicated at 13, a binding nut 14 coöperating therewith to retain the terminal of an electric conductor leading 45 from any suitable source of electricity, in a manner well known in the art. The insulating block is carried by a supporting bushing 15, in any suitable manner, said bushing being threaded at 16 to permit it to re- 50 movably engage a correspondingly threaded opening in the wall of an engine, or the like.

The insulating block is held in position by a nut 17 engaging the threads 18 of the bushing 15. Secured in the inner edge of the bushing 15 is a wire 19 having a bent 60 end, the extremity of which is provided with an enlarged or spherical portion 20 opposite the terminal 12, and coöperating with the latter to form the usual spark gap.

In operation the plug is connected with 65 the engine in the manner well understood in the art, and the current will flow through conductor 11 across the gap between the terminals 12 and 20 and through the bushing 16 to ground. By providing the spherical 70 portion 20, the grounded conductor more readily assimilates or absorbs the electric current passing from the terminal 12, thereby increasing the intensity or pressure passing from said terminal 12, thus producing 75 an intense rich spark sufficient to insure ignition under all conditions.

In Fig. 2 I have shown a modification which consists in supporting an insulating block 25 in a bushing 26, and retaining it 80 in position, by means of a plug 27, in the usual and well known manner. The lower end of the insulating block is of petticoat formation as indicated at 28, the conductor 29 extending through the insulator to form 85 a sparking terminal. The lower end of the petticoat portion 28 is provided with an external annular groove 30 to receive a coiled wire 31, one extremity of which is bent inwardly as indicated at 32 and is 90 provided with a spherical extremity 33 coöperating with the conductor 29 to form a spark gap. The other extremity is bent outwardly as indicated at 34 and terminates a sufficient distance from the edge of bushing 26 to form a spark gap. Extending from the inner edge of the bushing 26 is an electrode 35. In operation the wire 31 engages the groove 30 with sufficient friction to normally prevent relative rotation, 95 but yet permitting such rotation for purposes of adjustment. The current passing from the terminal 29 jumps the gap to the terminal 33 and passing through the wire 31 again jumps the gap from the extremity 105 34 to the bushing. Thus ignition of the explosive mixture within an engine is assured by reason of the double sparking at the two extremities of the wire 31, which for convenience, I will term a "bridge member". The terminal 35 is normally a sufficient distance from the bridge member 31.

to prevent the spark from jumping thereto, although it is obvious that should the gap at 34 be interrupted for any reason, the spark could then jump to the terminal 35 and the double spark be thereby secured. 5 Or if desired, the bridge member may be rotated so as to bring the terminal 34 near the terminal 35 so that the spark will jump to said terminal 35. If it is desired to eliminate the double sparking the terminal 34 is brought into contact with the terminal 35, and the plug will then operate in the same manner as the form illustrated in Fig. 1.

15 The modification in Fig. 3 employs the same form of insulating block 25 supporting bushing 26 and securing plug 27, the insulating block being also provided with the petticoat 28. In this form, however, the inner end of the central conductor 40 is bent 20 into a ring-like form as indicated at 41. Supported by the inner end of the insulating member 25 is a bridge member 42 provided with inwardly extended fingers 43, the extremities of which are made spherical as indicated at 44. The spherical ends 44 are located between the ring-like portion 41 and electrodes 45 secured to the bushing 26. By 25 this arrangement a double spark is secured, the current passing from the ring-like portion of conductor 40 to either or both of the spherical portions 44 and from thence to either of the terminals, thereby obtaining a spark at each gap. The bridge member 42 is rotatable to permit of adjustment of the electrodes 44 and 45.

Having thus explained the nature of my invention, and described an operative manner of constructing and using the same, although without attempting to set forth all of the forms in which it may be made, or all 40 of the forms of its use, what I claim is:—

1. An improvement in spark plugs comprising an insulating block, means for supporting the same, a central electrode extended through said block and having a sparking terminal, a grounded electrode, and a bridge member having an attaching portion encircling said insulating block, and provided 45 with sparking terminals coöperating respectively with the terminal of the central electrode and with the grounded electrode, said bridge member being rotatable on said insulating block, whereby the same may be 50 adjusted with respect to said grounded electrode to vary the gap.

2. An improvement in spark plugs comprising an insulating block, means for supporting the same, a central electrode extended through said block and having a sparking terminal, a grounded electrode, and a bridge member having an attaching portion encircling said insulating block, and provided 55

with sparking terminals, interposed between the terminal of the central electrode 65 and the grounded terminal, said bridge member being rotatable, whereby it may be adjusted with respect to said grounded electrode to vary the gap, said bridge member and said central electrode being relatively 70 shaped to maintain a uniform spark gap irrespective of such adjustment.

3. An improvement in spark plugs comprising an insulating block, means for supporting the same, a central electrode extended through said block and having a sparking terminal, a grounded electrode, and a bridge member having an attaching portion encircling the insulating block and rotatably supported, whereby it may be adjusted with respect to said grounded electrode to vary the gap, 80 said bridge member having a radially disposed angular arm the end of which terminates opposite to and is concentric with the terminal of the central electrode to maintain a uniform spark gap irrespective of the adjustment of said bridge member.

4. An improvement in spark plugs comprising an insulating block, means for supporting the same, a central electrode extended through said block and having a sparking terminal, a grounded electrode, and a bridge member having an attaching portion encircling said insulating block and rotatable thereon, said bridge member having a 90 radially disposed arm terminating in an angular portion forming a spark gap between the arm and the supporting means, said arm being adjustable by rotation of said bridge member with respect to said grounded electrode, said bridge member and said central electrode being relatively shaped to maintain a uniform spark gap irrespective of such adjustment.

5. An improvement in spark plugs comprising an insulating block, means for supporting the same, a central electrode extending through said block and having a sparking terminal, a grounded electrode, and a bridge member consisting of a wire coiled 100 around said insulating block and having its ends shaped to provide sparking terminals, coöperating respectively with the terminal of the central electrode and with the grounded electrode, said bridge member being rotatable on said insulating block, whereby the same may be adjusted with respect to said 110 grounded electrode to vary the gap.

In testimony whereof I have hereunto set my hand in presence of two subscribing witnesses.

HENRY H. MORETON.
